SCALP TREATING DEVICE

Florence Kelhoffer, Elizabeth, N. J.

Application August 1, 1945, Serial No. 608,177

16 Claims. (Cl. 128—60)

1

The present invention relates to mechano-therapeutic equipment, more particularly of the type to stimulate circulation to the scalp.

It is well known that beneficial effects are obtained by the exertion of sustained uninterrupted, constant localized strong mechanical pressure for a period of the order of fifteen minutes to one half hour against congested or otherwise affected localities of the body.

It is among the objects of this invention to provide a comparatively inexpensive apparatus for so treating the scalp, which apparatus is so designed that without adjustment, it fits practically any human skull of whatever size and shape and effects treatment of all cranial parts important to the revitalization of the entire scalp.

In the accompanying drawings, in which is shown one embodiment of the invention:

Fig. 1 is a fragmentary perspective view of the apparatus mounted on a suitable stand.

Fig. 2 is a plan view of the scalp treating apparatus embodying the invention, looking at the same in an upward direction relative to the position of the apparatus when in use.

Fig. 3 is a vertical section taken in a plane passing through line 3—3 of Fig. 2, and

Fig. 4 is a vertical section at right angles to the section of Fig. 3 taken in a plane passing through line 4—4 of Fig. 2.

In the drawings reference numeral 1 indicates a stand which has pivotally secured thereto one end of an arm 2. A spring 3 extends from the pivoted end of arm 2 to one of a series of hooks 4 on the stand 1 to place the arm 2 under any desired tension. The other end of arm 2 has pivotally mounted thereon a yoke 5 which is fastened to the top portion of a housing 6. The housing 6 is constituted of an upper rectangular portion 7 and a communicating lower flaring portion 8. A chair (not shown) is provided for the patient, the parts being so proportioned that the patient's skull enters the functional part of the scalp treating device hereinbelow described. The stand may be adjustable in height to accommodate patients of different heights.

An electric heating lamp 9 provided with current through wires 10, is suitably mounted in the upper portion of the housing to heat the apparatus and thus promote quicker blood circulation.

The flaring portion 8 of the housing consists of a front wall 9, two side walls 10 and 11 and a rear wall 12 (Fig. 2). On the interior of these walls, reinforcing and spring holding bars are disposed to form horizontally extending rectangular reinforcing and spring holding frames 13, 14 and 15,

2

which are equi-distant along the height of the housing. Reinforcing and spring holding bars 15' are disposed on the sides of the frame extending in a general vertical direction between the horizontally extending frames.

Disposed within the flaring portion 8 of the housing are three sets of coil springs. One set consists of springs which exert constant sustained uniform pressure on the scalp and contiguous portions of the skull, which pressure as is well known, stimulates circulation to the scalp, relieving congestion and otherwise improving the condition of the scalp. The other set consists of springs which act as a frame to hug the head and maintain the device in position thereon. This set of springs also aids in maintaining the first mentioned set under tension to exert the desired pressure. The third set consists of springs which function to secure the springs of the other two sets to the interior of the housing.

The first mentioned set of springs may comprise:

1. Coil springs 16, 17, 18 and 19 (Figs. 2 and 4) which extend in a generally longitudinal direction relative to the skull of the patient, and exert pressure on the epicranial portion indicated by reference character a.

2. Two sets of semi-circular or curved springs, one set consisting of the curved springs 20 and 21 (Fig. 3) engaging one side of the skull and the other set consisting of the curved springs 22, 23 (Fig. 2); these springs exert pressure on the superior auricular, anterior auricular and posterior auricular portions (indicated by b) on both sides of the skull.

3. Two springs 24, 24' (Figs. 2 and 3) which exert pressure on the frontal occipito-frontalis portion c of the skull, and

4. Coil springs 25, 26, the coil spring 25 being a heavier spring and approximately twice the diameter of the other springs, which springs exert pressure on the occipital part d of the occipito-frontalis portion of the skull.

The springs of the second mentioned set are the following: Coil spring 27 engaging the forehead, side springs 28, 29, 30 on the right hand side viewing Fig. 2, and side springs 31, 32, 33 on the left hand side viewing this same figure. These springs, plus the spring 26 hereinabove mentioned, form a frame which hugs the skull and maintains the apparatus in position.

The remaining springs which will be herein-after identified form the springs of the third set hereinabove mentioned.

The springs of the first mentioned set are

maintained under tension and are associated with each other and with the springs of the other two sets as follows:

A cross spring 34 (Fig. 3) has its ends suitably fastened to the frame 14 on the side walls 10, 11 of the housing. The rear ends of the springs 16, 17, 18 and 19 are fastened to this cross spring by suitable wire or other connection. A second cross spring 35 (Figs. 2 and 3) extends across the housing near the front wall thereof and has its ends fastened to the frame 14 on the opposite sides 10, 11 of the housing. The front ends of the springs 16, 17, 18 and 19 are fastened by means of a suitable wire connection with the cross spring 35.

The rear portions of the springs 16, 17, 18 and 19 are maintained under suitable tension by means of two springs 36, 37 (Figs. 2 and 3) which rest on the springs 16, 17, 18 and 19 and extend at right angles to the latter springs. The springs 36 and 37 are tensioned to exert pressure in a downwardly direction on these four springs 16, 17, 18 and 19 by having their ends suitably secured to side springs 38, 39. One end of spring 38 is fastened as at 40 to a longitudinal brace bar 15' on the back wall 12 of the housing and the other end is fastened as at 41 to a brace bar on the side wall 10 of the housing. One end of spring 39 is fastened as at 42 to a longitudinal brace bar on the back wall 12 of the housing, while the other end of this spring is fastened as at 43 to a brace bar on the interior of the side wall 11 of the housing.

Tension is maintained on the forward portion of the coil springs 16, 17, 18 and 19 by means of a pair of coil springs 44 and 45. Spring 45 is fastened to a forward portion of spring 18 and extends under tension from the top of spring 18 to side spring 31 extending diagonally across the front left corner (Fig. 2) of the housing and secured as at 46 to the front wall of the housing, and as at 47 to the side wall 11 of the housing. In similar manner, spring 44 is fastened to spring 17 and extends under tension from the spring 17 downwardly to side spring 28 which extends diagonally across the front right corner of the housing. One end of the spring 28 is fastened as at 48 to the side wall 11 of the housing and the other end is fastened as at 49 to the front wall 9 of the housing.

The spring 24 exerting pressure on the frontal occipito-frontalis portion of the skull has its ends fastened to springs 50, 51 which extend along the front wall of the housing and have their opposite ends fastened to the frames 13 and 15, respectively, as shown in Fig. 3 for the spring 51. A pair of side springs 52, 53 (Fig. 2) extend rearwardly from the extremities of spring 24 and are fastened at 54, 55 to the side walls 11 and 10, respectively. The spring 24 is thus maintained under the desired tension to exert the desired pressure.

Spring 24' is maintained under desired pressure by having its ends secured to diagonal springs 56, 57. One end of spring 56 is secured to front wall 9 as at 58 (Fig. 2) and the other to side wall 10 as at 59. One end of spring 57 is secured to front wall 9 as at 60 and the other end to side wall 11 as at 61.

Curved spring 22 (Fig. 2) has its ends fastened to springs 51 and 57 and is maintained under the desired tension by these springs. In like manner, curved spring 20 has its ends fastened to springs 50 and 56.

Large coil spring 25 has its end fastened to

frame 14 near the back of side walls 11 and 12, as indicated by reference characters 62, 63. The ends of curved spring 26 are secured to spring 25, as indicated by reference characters 64, 65. Side spring 30 has one end fastened to spring 26 as at 66 and the other end fastened to a spring 67 as at 68. Spring 67 is fastened at one end to spring 28 at 68' and extends rearwardly and is fastened as at 69 (Fig. 2) to large spring 25. Likewise, side spring 33 extends from the left hand side (Fig. 2) of spring 26 to a spring 70. The latter spring has one end fastened to spring 31 and extends rearwardly to spring 25 where it is fastened thereto as at 71.

Curved spring 23 has one end fastened to spring 67, and extends rearwardly and has the other end fastened to spring 38. Likewise spring 21 has one end fastened to spring 70 and the other end fastened to spring 39.

To maintain spring 25 under desired tension and to cause it to exert desired pressure, the following spring structure is used. A cross spring 72 extends parallel to the back wall of the apparatus, adjacent thereto and has its ends fastened to springs 38, 39. A curved spring 73 (Fig. 2) extends from spring 72 about the rear of spring 25, and is fastened to spring 70 as at 74. A coil spring 75 has one end fastened to coil spring 73 and the other end secured to spring 23 as at 76, the spring 75 maintaining spring 73 under tension so that it exerts pressure on spring 25. A second curved spring 77 passes about the back of spring 25 from spring 72 to spring 67, being fastened thereto at 78. A coil spring 79 has one end fastened to spring 77 and has the other end fastened as at 80 to spring 21. A heavy coil spring 81 is fastened to and extends from the mid-point of spring 25 to the rear wall of the housing where it is fastened thereto as at 82.

Thus it will be seen that the invention provides a scalp treating device comprising longitudinal coil springs for engaging and applying sustained pressure to the epicranial portion of the skull, transverse coil springs for applying sustained pressure to the occipital part of the occipito-frontalis portion of the skull, curved coil springs for applying sustained pressure to the superior auricular and other cranial parts important to the revitalization of the entire scalp. In operation, it has been found that a daily treatment of fifteen minutes duration causes improved blood circulation to the affected parts which effects renewal of stagnant blood and revitalizes the affected parts. In some cases, use of the apparatus may beneficially affect hair growth.

It will be further noted that the apparatus will fit substantially any skull, whatever the size and shape, since the spring parts automatically adjust themselves to the size and shape of the skull of the patient subjected to treatment.

As many changes could be made in the above construction, and many apparently widely different embodiments of this invention could be made without departing from the scope of the claims, it is intended that all matter contained in the above description, or shown in the accompanying drawings, shall be interpreted as illustrative and not in a limiting sense.

Having thus described my invention, what I claim as new and desire to secure by Letters Patent of the United States is:

1. In a scalp treating device, in combination, a longitudinally extending coil spring for engaging and applying pressure to the epicranium, a coil spring extending transversely to the longi-

tudinally extended spring for engaging and applying pressure to the frontal part of the occipito-frontalis portion of the skull, coil springs for engaging and applying pressure to the occipital part of the occipito-frontalis portion of the skull, and means for maintaining all of said springs under tension to exert the desired pressure on the aforementioned parts of the skull.

2. In a scalp treating device in combination, a longitudinally extending coil spring for engaging and applying pressure to the epicranium, a coil spring extending transversely to the longitudinally extending spring for engaging and applying pressure to the frontal part of the occipito-frontalis portion of the skull, coil springs for engaging and applying pressure to the occipital part of the occipito-frontalis portion of the skull and coil springs for engaging and applying pressure to the superior auricular and anterior auricular portions on both sides of the skull, and means for maintaining all of said springs under tension to exert the desired pressure on the aforementioned parts of the skull.

3. In a scalp treating device, in combination, a series of longitudinally extending coil springs in substantially parallel relationship for engaging and applying pressure to the epicranium, a pair of curved coil springs at each side of said series of springs for engaging and applying pressure to the superior auricular and anterior auricular portions of the skull on both sides thereof, a pair of coil springs extending transversely across the front of said series of longitudinally extending springs for engaging and applying pressure to the frontal occipito-frontalis portion of the skull and a pair of curved coil springs at the rear of said series of longitudinally extending springs for engaging and applying pressure to the occipital part of the occipito-frontalis portion of the skull.

4. In a scalp treating device, in combination, a housing, three sets of coil springs therein, one set of coil springs exerting sustained constant pressure on portions of the scalp, the second set of coil springs forming a frame adapted to fit the skull, and a third set of coil springs securing the other two sets to the interior of the housing and causing the first mentioned set to exert the desired pressure on the scalp.

5. In a scalp treating device, in combination, a housing, three sets of coil springs therein, one set of coil springs exerting sustained constant pressure on portions of the scalp, the second set of coil springs forming a frame adapted to fit skulls of different sizes and shapes and the third set of coil springs securing the other two sets to the interior of the housing and causing the first mentioned set to exert the desired pressure on the scalp.

6. In a scalp treating device, in combination, a housing, three sets of coil springs therein, one set of coil springs exerting sustained constant pressure on portions of the scalp, said set comprising a longitudinally extending coil spring for engaging and applying pressure to the epicranium, a coil spring extending transversely to the longitudinally extended spring for engaging and applying pressure to the frontal part of the occipito-frontalis portion of the skull, and coil springs for engaging and applying pressure to the occipital part of the occipito-frontalis portion of the skull, the second set of coil springs forming a frame adapted to fit skulls of different sizes and shapes and the third set of coil springs securing the other two sets to the interior of

the housing and causing the first mentioned set to exert the desired pressure on the scalp.

7. In a scalp treating device, in combination, a housing, three sets of coil springs therein, one set of coil springs exerting sustained constant pressure on portions of the scalp, said set comprising a series of longitudinally extending springs in substantially parallel relationship for engaging and applying pressure to the epicranium, a pair of curved coil springs at each side of said series of springs for engaging and applying pressure to the superior auricular and anterior auricular portions of the skull on both sides thereof, a pair of coil springs extending transversely across the front of said series of longitudinally extending springs for engaging and applying pressure to the frontal occipito-frontalis portion of the skull, and a pair of curved coil springs at the rear of said series of longitudinally extending springs for engaging and applying pressure to the occipital part of the occipito-frontalis portion of the skull, the second set of coil springs forming a frame adapted to fit skulls of different sizes and shapes and the third set of coil springs securing the other two sets to the interior of the housing and causing the first mentioned set to exert the desired pressure on the scalp.

8. In a scalp treating device, in combination, a stand, an arm having one end pivoted to the stand and the other end carrying a housing, means for maintaining the housing under desired tension, said housing containing three sets of coil springs therein, one set of coil springs exerting sustained constant pressure on portions of the scalp, the second set of coil springs forming a frame adapted to fit the skull, and a third set of coil springs securing the other two sets to the interior of the housing and causing the first mentioned set to exert the desired pressure on the scalp.

9. In a scalp treating device, in combination, a stand, an arm having one end pivoted to said stand and the other end carrying a housing, means for maintaining the housing under desired tension, said housing containing three sets of coil springs therein, one set of coil springs exerting sustained constant pressure on portions of the scalp, said set comprising a longitudinally extending coil spring for engaging and applying pressure to the epicranium, a coil spring extending transversely to the longitudinally extending spring for engaging and applying pressure to the frontal part of the occipito-frontalis portion of the skull, and coil springs for engaging and applying pressure to the occipital part of the occipito-frontalis portion of the skull, the second set of coil springs forming a frame adapted to fit skulls of different sizes and shapes and the third set of coil springs securing the other two sets to the interior of the housing and causing the first mentioned set to exert the desired pressure on the scalp.

10. A head applicator device comprising a hollow receiver member within which the head may be inserted and a plurality of tightly wound uninterrupted interlaced coil springs extending entirely across the interior thereof and forming a recess within which the head may be wedged with the tightly wound coils having tight elongated contact with the head.

11. A head applicator device comprising a hollow receiver member within which the head may be inserted and a plurality of tightly wound uninterrupted interlaced coil springs extending en-

tirely across the interior thereof and forming a recess within which the head may be wedged with the tightly wound coils having tight elongated contact with the head, said coil springs being looped and curved and overlaying one another.

12. A head applicator device comprising a hollow receiver member within which the head may be inserted and a plurality of tightly wound uninterrupted interlaced coil springs extending entirely across the interior thereof and forming a recess within which the head may be wedged with the tightly wound coils having tight elongated contact with the head, and a heater lamp carried by said receiver positioned above said coil springs.

13. A head applicator device comprising a hollow receiver member within which the head may be inserted and a plurality of tightly wound uninterrupted interlaced coil springs extending entirely across the interior thereof and forming a recess within which the head may be wedged with the tightly wound coils having tight elongated contact with the head, said coil springs extending transversely and longitudinally across the top and sides of the head.

14. A head applicator device comprising a hollow receiver member within which the head may be inserted and a plurality of tightly wound uninterrupted interlaced coil springs extending entirely across the interior thereof and forming a recess within which the head may be wedged with the tightly wound coils having tight elongated contact with the head, said coil springs being arranged in two layers, an inside contacting layer to contact the head and an outside layer to support and prevent undue expansion of the inside layer.

15. A head applicator device comprising a hol-

low receiver member within which the head may be inserted and a plurality of tightly wound uninterrupted interlaced coil springs extending entirely across the interior thereof and forming a recess within which the head may be wedged with the tightly wound coils having tight elongated contact with the head, the coil springs contacting the sides of the head and back of the neck consisting of curved loops extending downwardly around the head.

16. A head applicator device comprising a hollow receiver member within which the head may be inserted and a plurality of tightly wound uninterrupted interlaced coil springs extending entirely across the interior thereof and forming a recess within which the head may be wedged with the tightly wound coils having tight elongated contact with the head, said coil springs being arranged in three sets, one set serving to exert pressure on the scalp and skull, another set serving as a frame to hug the head and hold the device in position and maintain the first set under tension and a third set to secure the first two sets to the receiver.
